CAP-FEEDING APPARATUS

Harry E. Stover, Connellsville, Pa., assignor to
 Anchor Hocking Glass Corporation, Connells-
 ville, Pa., a corporation of Delaware

Application January 7, 1943, Serial No. 471,529

15 Claims. (Cl. 226—88.1)

My invention relates to Cap-feeding apparatus. It has to do, more particularly, with apparatus for feeding caps from a source of supply and applying them to containers, such as food containers and including jars, bottles, cans, et cetera, preparatory to sealing them on said containers.

This application is a continuation in part of my co-pending application Serial No. 427,966, filed January 23, 1942.

In said application Serial No. 427,966, I disclose a cap-feeding unit which is actuated by a container moved past the unit by a conveyer associated therewith. The unit is actuated by a passing container to feed a cap into a position where it is so supported that it will be engaged and withdrawn by such container so that it will be applied loosely to the container. The actuating means for the cap-feeding unit includes fluid-actuated mechanism which is controlled by means of a pilot valve, actuated by a trigger which is engaged by the passing container, and a main control valve actuated by the pilot valve.

One of the objects of my present invention is to provide controlling means for a cap-feeding unit of the type indicated which is more positive and efficient in operation.

Another object of my invention is to provide controlling means for a cap-feeding unit of the type indicated which is more simple in structure having but a few parts.

Another object of my invention is to provide controlling means for a cap-feeding unit of the type indicated which employs a single control valve.

Another object of my invention is to provide controlling means of the type indicated in the preceding paragraph which is of such a nature that the valve can be actuated only once by a single container moved into association therewith so that only one cap will be fed from the cap-feeding unit by each container.

Another object of my invention is to provide controlling means of the type indicated of such a nature that the valve cannot be reset until the feeding stroke of the cap-feeding unit is completed so that a cap must be fed from such unit each time the valve is actuated.

Another object of my invention is to provide controlling means of the type indicated for a cap-feeding unit which is of such a nature that it may be adjusted readily for actuation by containers of varying diameters.

In its preferred form, my invention contemplates the provision of a simple apparatus for feeding caps from a source of supply and apply-

ing them to containers such as jars, bottles, cans, et cetera. The apparatus is preferably employed with a continuously moving conveyer upon which the filled containers are placed at random. 5 Means is preferably provided in association with the conveyer for centering and maintaining containers centered on said conveyer. The containers are first moved by the conveyer to a cap-feeding and applying unit where caps or other closures are loosely positioned on the upper ends of the containers. The general structure of this unit is substantially like that disclosed in my co-pending application Serial No. 427,966, filed January 23, 1942.

10 15 The cap-feeding and applying unit consists of a magazine for receiving a stack of nested caps. This magazine is of such a nature that the stack of caps may be readily inserted thereinto and they will be held in proper nested relationship. Suitable wedge bars are disposed at the bottom of the magazine for supporting the lowermost cap. When these wedge bars are reciprocated, they separate the lowermost cap from the remainder of the stack of caps and allow it to fall downwardly while still supporting the stack of caps. A support is provided below the magazine for receiving each separated cap and supporting it in position to be engaged and withdrawn by a container moved beneath the cap-feeding and applying unit.

30 35 40 45 50 55 For controlling the movement of the wedge bars, I provide a fluid-controlled cylinder and piston unit. This cylinder and piston unit is actuated by a control trigger adapted to be engaged by a container moved beneath the cap-feeding and applying unit. This trigger actuates a main control valve which controls supply of fluid to said cylinder and piston unit. The control valve is of such a nature that it can be moved into actuating position only once by each passing container. Thus only one cap can be fed from the cap-feeding unit by each passing container and will drop into position to be engaged by such container. Furthermore, a locking mechanism is associated with the valve for locking it in actuating position, after it is once moved into such position by a passing container. This locking mechanism will prevent return movement of the valve to its original position until the feeding stroke of the cap-feeding unit is completed. This will insure that the cap-feeding unit will drop a cap for every stroke of the valve.

The preferred embodiment of my invention is illustrated in the accompanying drawings where-

in similar characters of reference designate corresponding parts and wherein:

Figure 1 is a top plan view of the cap-feeding and applying apparatus showing it associated with a sealing machine.

Figure 2 is a view, partly in top plan and partly in section, of the control valve of my apparatus.

Figure 3 is a vertical sectional view taken substantially along line 3—3 of Figure 2.

Figure 4 is a perspective view of the valve mechanism and associated parts of my unit.

Figure 5 is a view, partly in perspective and partly in vertical section illustrating the cylinder and piston unit of my apparatus.

Figure 6 is a top plan view, partly broken away, of my apparatus.

Figure 7 is a top plan view, partly broken away, of my cap-feeding unit showing the control valve in actuating position.

Figure 8 is a similar view showing how the locking mechanism prevents return movement of the valve after the cap-feeding stroke is started.

Figure 9 is a similar view showing the locking mechanism being released to permit return movement of the valve.

Figure 10 is a vertical sectional view taken substantially along line 10—10 of Figure 1.

Figure 11 is a vertical sectional view taken substantially along line 11—11 of Figure 10.

Figure 12 is a vertical sectional view taken substantially along line 12—12 of Figure 1.

With reference to the drawings, I have illustrated apparatus of the general type disclosed in my co-pending application, Serial No. 427,966. This apparatus comprises generally a table 1a (Figures 1 and 10) supporting a horizontal conveyer unit 1 on its upper surface. Above this conveyer in properly spaced relationship, a cap-feeding and applying unit 2 and a sealing head unit 3 are supported. The conveyer unit 1 may be of any suitable type and is driven continuously. As described in said co-pending application, the containers 4 are placed at random on the conveyer 1 and are moved in the direction of the arrows (Figures 1, 7 to 9, and 12) by the conveyer, suitable means being provided for centering the containers on the conveyer.

My invention is not limited to any particular type of container and cooperating cap but for illustrative purposes I have shown in Figure 12 a jar 4 having its upper end shaped to receive a cap of the type indicated by the numeral 5. This cap preferably embodies a substantially disk-like portion 6 which has a depending annular skirt 7 which carries an annular gasket 8 therewithin. When a cap is forced downwardly onto the upper end of the container, the frictional contact of the gasket with the upper end of the container will aid in maintaining the cap in position and will seal the cap on the container.

My cap-feeding and applying unit 2 is preferably disposed directly adjacent the sealing unit 3. They are both supported by a horizontally disposed casting 9. The casting 9 is supported at a point spaced above the conveyer 1 by means of a plurality of vertically disposed posts 10. As described in my application, Serial No. 418,401, the casting 9 may be adjusted vertically on the posts 10 to vary the height of the units 2 and 3 above the conveyer 1 for different heights of containers.

The cap-feeding and applying unit comprises a plate 133 which is suitably mounted on the casting 9 over a large opening 25a (Figure 1) in the casting. This plate 133 has a portion 134 (Fig-

ures 10 and 12) which extends down into the opening 25a. The plate 133 is held in position on casting 9 by means of dowel pins 135 (Figure 1) extended into openings formed in casting 133. Pins 135 fit into sockets 135b in casting 9 so that plate 133 may be removed readily from casting 9. The plate 133 is provided with a centrally disposed opening 136 which is of the proper size to permit the caps, to be applied to the containers, to drop freely therethrough. The plate 133 carries four upstanding posts 137 which are spaced circumferentially around the opening 136. These posts 137 are adapted to receive a stack of the nested caps.

As described in my co-pending application Serial No. 427,966, for controlling the feed of the caps downwardly through the opening 136, I provide the following structure. This structure embodies a pair of cap-separating wedge members 138. These wedge members 138 are disposed tangentially to the opening 136, as indicated best in Figures 1 and 6 to 10. They are mounted for longitudinal movement in recesses 138a formed in the lower surface of the plate 133 (Figure 12). The recesses 138a extend substantially tangential to opening 136 and are in communication therewith at their inner edges. The lower wall of these recesses is formed by a plate 133a which is secured to the lower surface of plate 133 and which has a central opening 136a in alignment with opening 136. The members 138 are connected together at one end by a bar 139 (Figure 1) in such a manner as to permit slight movement of the wedge bars relative to bar 139 so that they will properly align and position themselves in recesses 138a as described in my co-pending application Serial No. 427,966. The other ends of wedge bars 138 are connected together in a similar manner by a bar 140.

The bar 139 is engaged by the outer end of a pin 141 (Figure 1) which is mounted for axial movement in a bearing member 9a disposed on casting 9 (Figure 3). The outer end of the pin 141 is provided with a head 142 disposed within housing 143. This cylindrical housing 143 is in alignment with bearing member 9a and has a closed outer end 144. Within this housing a compression spring 145 is provided. This spring has one end bearing against the closed end 144 of the housing and its other end bearing against the head 142 on pin 141. Thus, the spring 145 normally forces the pin 141 in one direction as shown in Figure 1.

The spring 145 also serves to keep the bar 140 in contact with the outer end of a piston rod 146 which is diametrically opposed to pin 141. This piston rod 146 (Figures 1, 5 and 10) is carried by a piston 146a disposed in a cylinder 147 carried by the casting 9. The piston 146a is provided with a projection 146b on its outer end which extends into a socket 146c in the closed end of cylinder 147 but keeps the main part of the piston spaced from such closed end when it is moved to its extreme position to the left of Figure 10. The piston 146a is held normally in the position indicated in Figure 10. It will be apparent that when the piston is reciprocated, the members 138 will be reciprocated also.

The wedge members 138 are of the shape described in my co-pending application Serial No. 427,966. They operate in the manner described in said application when reciprocated to drop a cap downwardly through openings 136 and 136a. The members 138 are held in their initial position (Figure 1) by spring 145. When the mem-

bers 138 are moved in the opposite direction by outward movement of the piston 146a, the lowermost cap will drop through the opening 136 as described in my co-pending application.

It will be apparent that the entire cap feeding unit consisting of plate 133, posts 137, carried by such plate, and members 138, mounted for longitudinal movement in guides in said plate, together with bars 139 and 140, can be removed readily and be replaced with a similar unit for different size caps. The removal of this unit is facilitated because pin 141 is not connected to bar 139 and piston rod 146 is not connected to bar 140. The wedge members 138 may be removed quickly and easily for cleaning or replacement from the plate 133 by disconnecting the bars 139 and 140 from the ends thereof.

The cap released from the stack will drop downwardly onto a tongue member 162 (Figure 12). This member 162 extends beneath the opening 136a in plate 133a. It is fastened on the lower end of a vertical pin 162a which is mounted for rotation in aligning openings formed in members 133 and 133a. The upper end of the pin 162a has a handle member 162b pinned thereon. A downwardly pressed ball and spring latch 162c is provided at the lower side of handle 162b and bears against the upper surface of plate 133. The ball latch member 162c normally extends into a socket 162d in plate 133 and prevents swinging of handle 162b and, consequently, rotation of tongue 162 about the axis of pin 162a. However, the handle 162b can be swung away from its original position with slight force and thus will produce swinging movement of tongue 162 from beneath the opening 136a. When the tongue 162 is in normal position, as shown in Figure 12, the rear edge of the dropped cap is supported thereby. The forward edge of the cap is supported at diametrically opposed points by lugs 165. As shown in Figure 12, the cap will be supported in downwardly tilted position. The plate 133a is so formed that guide portions 165a are provided at each side thereof which will prevent lateral movement of the cap as it is withdrawn from the supporting members 162 and 165 by a container being moved along by the conveyer 1. The members 165 are secured to guide portions 165a and although they are spaced a distance such that the cap will rest thereon, they are so spaced laterally that the upper end of the container will pass therebetween, it being understood that the cap is slightly greater in diameter than the upper end of the container. Furthermore, the members 165 are so placed longitudinally and vertically, that the resulting angle of the tilt of the dropped cap is such that the upper end of the container will pass under the rear edge of said cap, and it will engage with the inner side of its forward edge, and since said cap is merely guided but not restrained in any way, it is easily removed by the container without danger of upsetting said container. Centering lugs 165c (Figure 1) are provided ahead of lugs 165 and are adapted to engage the upper end of the container to center it exactly relative to opening 136.

As previously explained, the entire cap-feeding unit is carried by plate 133 and can be removed readily and be replaced with a unit for feeding caps of a different size. Furthermore, at any time, the tongue 162 may be swung away from aligning openings 136 and 136a to facilitate removal of a dropped cap, if it is desired to remove it.

When the conveyer moves a container beneath the cap-feeding unit 2, the upper end of the container will engage the skirt of the inclined cap disposed in the position indicated in Figure 12.

5 This will withdraw the cap from its supports and position it on the upper end of the container. The cap and container will be moved along until they pass into association with the sealing unit 3 which will seal the cap on the container in a manner described in my co-pending application, Serial No. 418,401.

In order to supply steam to the cylinder 147 to actuate the cap-feeding unit, I provide means which is actuated by movement of the container 15 with the conveyer into a position below the cap-feeding and applying unit. As illustrated best in Figures 7 to 10, this means comprises a small roller 186 which is held in a fixed position by a pin 186a (Figure 10) on the lower edge of one of the guide portions 165a of plate 133a. This member 186 is located directly below the aligning openings 136 and 136a slightly forwardly of pin 141 and piston rod 146 as shown best in Figure 1. At a point almost laterally opposed but spaced 20 forwardly slightly, the washer member 187 is disposed on the other guide portion 165a of plate 133a. A pair of pins 188 (Figures 7 to 10) are supported by a horizontal guide 188a beneath washer 187 and this guide prevents the removal of washer 187 but permits free lateral movement of the washer to a considerable extent.

A control valve 189 is associated with the washer member 187. This control valve is illustrated best in Figures 3, 4, 7, 8 and 9. It comprises a segmental body 190 which is mounted for pivotal movement in a segmental notch 191 which is formed in the outer edge of a block 192. This block 192 is provided with an integral cylindrical extension 193 (Figures 4 and 5) on its opposite end which extends within a cylindrical socket 147a (Figure 5) formed as a part of cylinder 147 and in axial alignment therewith. The extension 193 is prevented from rotating or moving axially in socket portion 147a by means of a 45 setscrew 194 (Figure 6) which is threaded through the wall of socket 147a and engages extension 193.

The segmental body 190 is supported on a shelf-like portion 195 of block 192 and is pivoted thereto by means of a pin 196 which extends through member 190 and into an opening 197 formed in portion 195. The inner curved surface 198 of body 190 will be in close contact with the inner arcuate wall surface 199 of the 55 notched portion 191, as shown best in Figures 7, 8 and 9. A cap 200 is mounted on the upper side of block 192 and is properly aligned therewith by means of a groove 201, formed in the underside of the cap, which cooperates with a 60 rib 202 formed on the top surface of the block. Aligning openings 203 and 204 are provided in the cap and block for receiving screws 204a (Figure 3) which keep such members in proper association. The upper end of pin 196 will extend into an opening 197a formed in cap 200.

Thus, member 190 is mounted on the block 192 for rotation about the axis of pivot pin 196. Rotation in one direction is limited by a stop pin 205, carried by the block and extending into notch 191, which contacts with a stop shoulder 206 formed in the outer lower surface of body 190. A compression spring 207 normally keeps member 190 in the position indicated in Figure 2, where pin 205 will be in contact with shoulder 75 206. One end of this spring bears against the

vertical wall 208 of a recessed portion 209 formed in body 190 and fits over a pin 210 carried thereby. The other end bears against the short arm 211 of a latch 212 which is in the form of a bell crank lever. A pin 213 on arm 211 receives this end of the spring. Latch 212 is pivoted, as at 214, in a recessed portion 215 formed in the upper surface of block 192. The lever 212 is disposed at one side of a ledge 216, provided in recessed portion 215, while the spring 207 is disposed at the opposite side thereof. The outer end of the long arm of latch 212 is provided with an inwardly projecting latch portion 217. This vertical latch portion 217 is adapted to cooperate with a vertical keeper portion or notch 218 formed in the outer side of body 190. However, when the body 190 is in the position shown in Figure 9, where it will be normally held by spring 207, the latch portion 217 will not extend into keeper 218 but will instead contact with the curved face 198 of member 190. The spring 207 also serves to swing the latch 212 about pivot 214 and urge portion 217 inwardly. Adjacent its outer end and the latch portion 217, the latch carries an upstanding pin 219. This pin is carried on an extension 220 which extends out beyond the edge of block 192 and cap 200 (Figure 5).

The inner curved face 198 of body 190 is provided with a vertically disposed chamber 221 formed therein which is completely closed except at its outer side. This chamber 221 is sufficiently wide that it can connect a central vertical slot 222, formed in wall surface 191 of block 192, with either a parallel vertical slot 223 or a parallel vertical notch 224, which are also formed in surface 191, depending upon the position of body 190. The slots 222 and 223 are of substantially the same height as chamber 221 and are disposed at substantially the same level. The notch 224 is adapted to serve as an exhaust opening and communicates with the recessed portion 215 formed in the block 192. It is formed by drilling a hole completely through the block 192 as shown in Figure 3.

The slot 223 is at one end of a steam-supply passageway 225 (Figure 6) which extends through block 192 and extension 193. A steam line is adapted to be connected to a threaded connection 226 at the opposite end of this passageway. The slot 222 is at one end of a passageway 227 (Figure 10) which leads through block 192 and extension 193. The opposite end of this passageway is in communication with an opening 228 extending through the wall of cylinder 147 at the closed end thereof, that is, the left-hand end of Figure 10. The opposite end of the cylinder is provided with a vent opening 229.

The piston 146a is ordinarily in the position indicated in Figure 10, being held in this position by means of spring-pressed pin 141. At this time the valve body 190 will be in the position indicated in Figure 6. The chamber 221 in the valve body will be in such position that the slot 223 will be closed but the slot 222 will be connected thereby to the exhaust opening 224. Thus, steam will have exhausted from the closed end of cylinder 147, through opening 228, passageway 227, slot 222, chamber 221 and opening 224 to the atmosphere.

When a container is moved into position to engage washer 187, the washer is moved, as indicated in Figure 7, and will rotate valve body 190. This will move chamber 221 to such a po-

sition that the slot 222 will be connected to slot 223 while the exhaust opening 224 will be closed. Consequently, steam will flow from supply passageway 225, through slot 223, chamber 221, slot 222, passageway 227, opening 228, into the closed end of cylinder 147. Thus, the piston 146a will be moved to the right (Figure 10) causing a similar movement of cap-feeding bars 138.

When the washer 187 is moved to a sufficient extent, moving valve body 190 inwardly, as shown in Figure 8, against resistance of spring 207, the latch portion 217 will snap into keeper 218. This will prevent return movement of valve body 190, the spring 207 tending to cause this return movement. Return movement of valve body 190 will be precluded until the wedge bars 138 complete their feeding stroke. At this time, a cam portion 230 (Figure 5) formed on the lower surface of bar 140, adjacent its outer end, will strike the pin 219, carried by latch 212, as shown in Figure 8. This will swing latch portion 217 out of notch 218. Valve body 190 will then be rotated back to its original position by spring 207 (Figure 9) and will reach the final position shown in Figure 2. Return movement of the valve body 190 will be permitted by washer 187 after the container has moved past the washer. In this position, chamber 221 will again connect slot 222 with exhaust opening 224, permitting exhaust of steam from the closed end of cylinder 147 and, consequently, permitting spring-pressed pin 141 to move wedge bars 138 and piston 146a back to their original positions.

It will be apparent that reciprocation of the wedge bars 138 in the manner indicated drops a single cap into the position indicated in Figure 12. In this position, it will be engaged and withdrawn by the container which has previously moved washer 187 to actuate the cap-feed. With the arrangement indicated, the valve can be set but once for each container, so that only one cap can be dropped by a container. The valve cannot be reset until the feed stroke of the cap-feeding wedge bars 138 has been completed and the container has passed the actuating washer 187 of the valve. This means that the cap feed can drop only one cap for every setting or actuating of the valve and there can be but one setting for the valve for each passing container.

It will be apparent from the above description that I have provided controlling means for a cap-feeding unit which is more positive and efficient in operation. It is simple in structure, having few parts. It employs a single control valve of such a nature that one cap only will be fed from the unit by each container. Furthermore, a cap must be fed from the unit each time the valve is actuated by a container.

Various other advantages will be apparent from the preceding description, the drawings and the following claims.

Having thus described my invention, what I claim is:

1. In a cap-feeding apparatus, a source of supply of caps, movable means for feeding caps successively from said source of supply, control means for moving said movable means and including a movable control member, means for locking said control member after it has been moved to actuating position, and means for releasing said control member as said movable cap-feeding means nears the extent of its movement.
2. In a cap-feeding apparatus of the type de-

scribed wherein conveyer means is provided in association with said apparatus, said apparatus comprising a source of supply of caps, movable means for feeding caps successively from said source of supply, control means for moving said movable means and including a movable control member, said control member being moved to actuating position upon movement of a container by the conveyer into association with said cap-feeding apparatus, means for locking said control member after it has been moved to actuating position, and means for releasing said control member as said movable cap-feeding means nears the extent of its movement.

3. In a cap-feeding apparatus, a source of supply of caps, a movable member for feeding caps successively from said source of supply, fluid-actuated means for moving said movable member, means for controlling actuation of said fluid-actuated means, said means comprising a movable valve, means for locking said valve after it has been moved to actuating position, and means for releasing said valve as said movable cap-feeding member nears the extent of its movement.

4. In a cap-feeding apparatus of the type described wherein conveyer means is provided in association with said apparatus, said apparatus comprising a source of supply of caps, a movable member for feeding caps successively from said source of supply, fluid-actuated means for moving said movable member, means for controlling actuation of said fluid-actuated means, said means comprising a movable valve, said valve being moved to actuating position upon movement of a container by the conveyer into association with said cap-feeding apparatus, means for locking said valve after it has been moved to actuating position, and means for releasing said valve as said movable cap-feeding member nears the extent of its movement.

5. Apparatus according to claim 4 wherein the valve is moved to actuating position by a trigger which is engaged by the container carried by the conveyer.

6. Apparatus according to claim 4 wherein said valve comprises a rotatable body portion for selectively connecting said fluid-actuated means to a supply line or to a vent.

7. Apparatus according to claim 4 wherein said fluid-actuated means comprises a cylinder and piston unit, said valve comprising a rotatable body portion for connecting said cylinder to a fluid supply line or to a vent.

8. Apparatus according to claim 2 wherein a trigger is provided for moving said control member, said trigger being in position to be engaged by a container moved into association with said cap-feeding unit.

9. Apparatus according to claim 2 wherein said

valve comprises a rotatable body portion for selectively connecting said fluid-actuated means to a supply line or to a vent.

10. Apparatus according to claim 3 wherein said valve comprises a body portion movable to positions to connect a supply line to said fluid-actuated unit or a vent to said unit.

11. In a cap-feeding apparatus, a source of supply of caps, a movable member for feeding caps successively from said source of supply, fluid-actuated means for moving said movable member, means for controlling actuation of said fluid-actuated means, said means comprising a valve of segmental form having a chamber formed in the face thereof, said valve being mounted for rotation on a valve block having a plurality of passageways formed therein, said passageways including a passageway connected to said fluid-actuated means, a passageway connected to a source of supply of fluid and a vent passageway, said valve being movable from a normal position where it connects the vent passageway to the passageway connected to said fluid-actuated unit to an actuating position where it connects said fluid supply passageway to said passageway which is connected to said fluid-actuated means, and a latch member associated with said valve body for maintaining it in actuating position after it is moved into such position.

12. Apparatus according to claim 11 wherein means is provided for releasing said latch member as the cap-feeding member nears the extent of its movement.

13. Apparatus according to claim 11 wherein said cap-feeding member is provided with a cam portion which engages said latch member and releases it as said cap-feeding member nears the extent of its movement.

14. Apparatus according to claim 11 wherein a spring is provided which tends to maintain said valve body in normal position and wherein said cap-feeding member is provided with a cam portion which engages said latch member and releases it as said cap-feeding member nears the extent of its movement.

15. A cap-feeding unit comprising a magazine for supporting a stack of the caps, said magazine having an opening at the bottom thereof through which the caps are adapted to drop, means for controlling the feed of caps through said opening, a tongue member supported adjacent said opening and normally projecting beneath said opening, said tongue member being carried by the lower end of a rotatable pin, a handle member on the upper end of said pin, said handle member having a ball type plunger associated with its lower surface and adapted to cooperate with a receiving socket for normally holding the tongue in operative position.
